Henry R. Williamson,

By J. Stanton Boyden,

Attorney.

UNITED STATES PATENT OFFICE.

HENRY R. WILLIAMSON, OF ATLANTA, GEORGIA.

SAFETY DEVICE FOR LOCOMOTIVES.

Application filed March 29, 1924. Serial No. 702,903.

To all whom it may concern:

Be it known that I, HENRY R. WILLIAMSON, citizen of the United States, residing at Atlanta, in the county of Fulton and State 5 of Georgia, have invented certain new and useful Improvements in Safety Devices for Locomotives, of which the following is a specification:

This invention relates to locomotives and 10 more particularly to means for controlling the flow of steam from the boiler to the different devices to be supplied.

It frequently happens that, due to accident or other causes, it is desirable to be 15 able to quickly and completely shut off the supply of steam from the boiler to the various devices normally connected therewith. In case of collision or derailment of the locomotive, it is further desirable to provide 20 automatic means for shutting off the supply of steam; so as to prevent the possibility of scalding the crew.

The object of the present invention is to combine, in a single, simple and efficient device, means whereby the steam may be manually 25 shut off, from any one of a plurality of different points in the cab, and also means whereby a severe shock to or angular displacement of the locomotive will serve 30 to automatically shut off the flow of steam.

In order that the invention may be readily understood, reference is had to the accompanying drawing, forming part of this specification, and in which:

Figure 1 is a vertical, sectional elevation showing conventionally a locomotive cab and illustrating my invention as applied thereto;

Figure 2 is a detail vertical section on an 40 enlarged scale through the steam turret and controlling valve, parts being shown in elevation;

Figure 3 is a fragmentary transverse section on the line 3-3 of Figure 1; and

Figures 4 and 5 are fragmentary detailed views on an enlarged scale, showing different positions of the parts constituting the valve restraining and releasing means.

Referring to the drawings in detail, the usual locomotive boiler is indicated at 1, and the cab at 2. The numeral 3 designates the usual steam distributing box or turret from which extend a plurality of pipes 4 to the various devices of the locomotive to be supplied with steam. This turret or distributing box is mounted upon and connected

with the boiler by means of a neck or nipple 10, projecting from the lower side thereof.

I propose to provide means whereby the supply of steam from the boiler to the turret or distributing box may be instantly cut off, and to this end, I mount upon the top of the turret a cylinder 5, in which reciprocates an elongated piston-shaped valve member 6, having its lower end shaped to 60 form a valve 7, arranged to cooperate with a valve seat 8, surrounding the upper open end of the nipple 10. Guide rods 9 preferably extend downwardly from the lower end of the piston member 6 to steady the 65 same.

Within the hollow piston member 6 and cylinder 5, is located a compression spring 11, the lower end of this spring bearing against the piston member and the upper 70 end bearing against a plate 12. This plate is engaged, in turn, by the lower end of an adjustable plug 13, screw threaded into a box at the upper end of the cylinder 5; so that by turning this plug, the tension on the spring 11 may be adjusted as desired. From the above, it will be apparent that the spring 11 tends constantly to force the 75 valve 7 toward its seat 8, or, in other words, to close the valve and shut off the supply 80 of steam.

Extending loosely down through the plug 13, is a rod 14, the lower end of which is secured to the bottom of the piston member 6, and the upper end of this rod is pivoted 90 to one end of a lever 15, itself pivotally supported at 16 on a standard 17, mounted on the turret or other convenient part. The other end of the lever 15 is provided with a hole 15^a (see Figure 5) which is adapted 95 to normally engage over a pin 19, carried by a standard 18, mounted on the boiler or other suitable support.

Interposed between the lever 15 and standard 18, however, is one end of a rock shaft 100 20, the other end of which is journaled in a bushing 21 in the wall of a cab. This rock shaft, or at least the end thereof adjacent the standard 18, is of relatively flat wide cross section, as shown in Figures 4 and 5, and such end is provided with an opening 22, adapted to fit over the pin 19, such opening being, however, considerably larger than said pin.

The parts being in normal position, as 110 shown in Figure 4, it is obvious that if the shaft 20 is rocked or angularly displaced, as

shown in Figure 5, the end portion thereof will be canted or inclined in such a way as to push the end of lever 15 off of the pin 19, thus releasing such lever and permitting the 5 spring 11 to immediately throw the valve member 6 down to closed position. As shown in Figure 5, the lever 15 is slightly flexible in order to permit the end thereof to be deflected and pushed off of the pin 19, 10 as illustrated, and it is sufficiently resilient to prevent the ordinary vibration of the locomotive from dislodging it from the pin.

In order to operate the rock shaft and thus release the valve restraining means, I 15 secure to the rock shaft, at a suitable point, an arm 23, and to this arm, I attach one end of a light rope or cable 24, similar to a bell cord, such rope or cable being led through a series of eyes or guides 24, longitudinally of the cab, and anchored at its free end to a fixed support. It is obvious, therefore, that a pull upon the cord or cable 24 will result in rocking the shaft 20 and releasing the valve as described, and it will 20 be noted that this cord can be grasped and pulled from any one of a plurality of positions in the cab. The cord may be extended so as to run along the cab on both sides thereof, if desired, so as to be within easy 25 reach of either member of the crew.

As above stated, I also contemplate the provision of means whereby a severe shock or overturning of the locomotive will result in automatically releasing the steam valve. 30 To this end, I provide a weight 28 of any suitable shape, shown in Figure 1 as a ball, and connect this weight by means of a chain 27 or the like to another arm 26, secured to the rock shaft 20. I support the weight 28 in a suitable container, shown as a shallow 35 cup 29, preferably located outside of the cab and on the roof thereof. It will therefore be understood that in case of collision or derailment, the ball 28 will be thrown out of the cup 29, and as it falls, will exert a pull on the chain 27, which, in turn, will actuate the rock shaft 20, and thus release the restraining means and permit the valve to 40 close, under the influence of the spring 11.

It will thus be seen that I have provided 45 a single releasing means capable of being operated either manually or automatically, and it is thought that the many advantages

of my improved arrangement will be readily appreciated without further discussion. 55

What I claim is:—

1. The combination with the steam distributing box or turret of a locomotive, of a valve for controlling the supply of steam to said box, means constantly tending to close 60 said valve, restraining means for normally holding said valve open, automatic means, responsive either to shock or to angular displacement of the locomotive for releasing said restraining means and permitting said 65 valve to close, and manual means independent of said automatic means for operating said releasing means.

2. The combination with the steam distributing box or turret of a locomotive, of 70 a valve for controlling the supply of steam to said box, means constantly tending to close said valve, restraining means for normally holding said valve open, a rock shaft extending longitudinally of the locomotive 75 cab for releasing said restraining means, and independent manual and automatic means for operating said rock shaft.

3. The combination with the steam distributing box or turret of a locomotive, of a 80 valve for controlling the supply of steam to said box, means constantly tending to close said valve, restraining means for normally holding said valve open, a weight separate 85 from said restraining means and supported outside of said box in such manner that it will be dislodged by shock to or angular displacement of the locomotive, said restraining means normally functioning independent of said weight and means whereby 90 said weight, when thus dislodged, will operate automatically to release said restraining means and cause said valve to close.

4. The combination with the steam distributing box or turret of a locomotive, of a 95 valve for controlling the supply of steam to said box, means constantly tending to close said valve, a weight supported outside of the locomotive cab, restraining means normally independent of said weight for holding 100 said valve open, means for releasing said restraining means, and flexible means connecting said weight with the said releasing means.

In testimony whereof I affix my signature.

HENRY R. WILLIAMSON.
